(57) **CLAIM**

The ornamental design for a packaging case, as shown and described.

DESCRIPTION

The file of this patent contains at least one drawing/photograph executed in color. Copies of this patent with color drawings/photographs will be provided by the Office upon request and payment of the necessary fee.

FIG. 1 is a front, top and left side perspective view of a packaging case showing our new design;

FIG. 2 is a front view thereof;

FIG. 3 is a rear side view thereof;

FIG. 4 is a top plan view thereof;

FIG. 5 is a bottom plan view thereof; and,

FIG. 6 is a right side view thereof, the left side view being a mirror image of FIG. 6.

The evenly-spaced broken lines illustrate portions of the packaging case that form no part of the claimed design. The dash-dotted lines denote the boundary of the claim and form no part of the claimed design. The blank areas surrounded by the dash-dotted lines form no part of the claimed design.
